Application July 14, 1943, Serial No. 494,596

31 Claims. (Cl. 66—86)

This invention relates to warp-knitting machines, a well known class wherein numerous warp yarns are fed from one or more supplies or reels and through one or more banks of yarn guides for manipulation into warp-knitting fabric by cooperation with needles and other conventional knitting instruments; a typical prior instance of such a machine being the double tricot knitting machine shown in prior copending application of this applicant, Serial No. 455,186, filed August 18, 1942.

In the warp-knitting machine of said prior application there is provided an arrangement for relieving the yarns, as they are manipulated, during knitting cycle after cycle, from the greater part of burden of having to start into rotation each yarn reel at that part of each cycle when feed is demanded by the action of the knitting instruments; this object being attained by the use of a power driving mechanism, with timed clutch, and a yarn pilot or guide rod which is resiliently supported but is caused to yield by the pull of the yarns traveling over it, such pilot or guide rod being connected through a shipper device to operate the driving clutch and impose the driving force upon the reel. The reel is thus power-rotated for a small arc of movement by the combined tension pull of the yarns and power drive, which movement is thereupon caused to cease as the reel advance supplies the needed yarn or causes yarn slack, by reason of which the pilot relaxes or terminates the clutch drive and on the contrary operates or imposes the action of a brake to retard or stop the rotation of the reel; both the driving clutch and the retarding brake being frictional in character and comprising friction shoes bearing upon friction disks or drums with greater or less pressure, under the described control of the pilot.

Such prior mechanism, particularly in regard to the reel retarding or braking action, in respect to which the mechanism may be considered of utility irrespective of the power driving action on the reel, possessed a certain objection by reason of the gradual changes of operating conditions during the consumption of the yarns as drawn from an initially full reel; the diameter of the body of yarn upon the reel gradually decreasing from an initial or full diameter to a minimum depleted or empty diameter. During such progressive depletion of the yarn supply the radius of the yarn supply and therefore the leverage and effectiveness of the tangential pull of the yarn upon the reel tends progressively to decrease, and this naturally renders somewhat more and more

difficult the action in each knitting cycle of starting or accelerating each feeding rotation of the reel, whether turned by the pull of the yarn alone or by such pull supplemented by a power drive 5 means such as disclosed in said prior application. In other words, the cyclical need of starting reel rotation became gradually more difficult, tending to introduce irregularities in action and even variations in the fabric produced. Not merely does the progressive reduction of yarn radius tend to increase relatively the inertia to be overcome in each shift of the reel, but obviously in successive cycles the angle of each rotation and the speed thereof are proportionately greater, to the detriment of uniformity. It is true that the depletion 10 of yarn reduces the mass and inertia of the reel and contents, but this factor is outweighed by the other factors mentioned. These described drawbacks pertain to prior prevailing machines generally and to said prior application as one illustration thereof.

To overcome partially the recited conditions and recognized drawbacks, a prevailing plan has been the manual one of periodically decreasing 15 the stress of the long tensioning springs which bear upwardly and support the yarn pilot rod, namely, by lowering little by little during the exhaustion of the yarn supply the lower abutments of such tensioning springs, shown in the prior application. Such gradual readjustment of the springs by hand causes a readjustment or lowering of the operative range of oscillation of the yarn-tensioning pilot and thus in turn causes a change in the position of the brake-relaxing 20 rocklever or shipper in a sense to actuate the relaxing of the brakes somewhat earlier and to a greater extent, in each cycle, thereby to facilitate an easier rotating of the reel when the point arrives to supply the needed yarn. But such lowered range and angle of the pilot swing and the haphazard nature of the control are objectionable. The manual attention or control during the depletion of the yarn, however, is inadequate to ensure uniformity in the product fabric, and they 25 give an irregular action, with occasional variations appearing in the fabric. The flow of yarn from the pilot to the knitting point gradually varies in angle, especially in relation to the swinging arms that carry the pilot, and this changes 30 the relations and cooperations of the elements.

The impairment of fabric uniformity may be further explained as follows. Each lowering of the tension spring abutments decreases their tension and shifts or lowers the range of pilot action, 35 by which result the brake shoes progressively

relax and so assist in the operations of the reel to supply the needed yarn through cycle after cycle. But the lowering of the spring tension causes a lowered yarn tension, and this makes itself felt by a gradually looser fabric as knitted from the nearly depleted yarn. This while appreciable is not always apparent, but is accompanied by a looseness and sometimes fluttering of the yarn between the pilot rod and the knitting elements, and so is apt to cause defects in the fabric, and require stoppage of the machine.

These prevailing drawbacks apply, in the case of machines having reel braking means whether or not having reel driving means. The machine of said prior application has such a warp reel power drive, which is responsive, as is the brake, to the swinging of the yarn tension rod or pilot; and in respect to this drive the importance also exists of maintaining uniformity of operation throughout the gradual exhaustion of the yarn. This general problem or drawback is what concerns the present invention, which is intended to afford a regularized and automatic control of the yarn tension and supply throughout the varying conditions caused by the decreasing diameter of the yarn supply on the reel.

The main object of the present invention is to afford a warp-knitting machine of improved reliability of action, especially in respect to drawbacks due to the described varying conditions during the consumption of yarn from the supply reel. A particular object is to provide automatic regulating means for modifying the control of the reel braking means by which the braking action or friction thereof is progressively decreased or relaxed accompanying the gradual depletion of the yarn supply on the reel, thereby practically offsetting the effect of the change of conditions during the consumption of the yarn from the supply reel. A further object is to provide practical mechanisms and connections for carrying out such regulation in a simple and effective manner.

For these purposes the present invention may be described in one aspect as consisting in a warp-knitting machine wherein is a brake shoe, or a cooperating opposite pair thereof, movably mounted to apply retarding effect upon a disk or drum connected with the yarn reel; and in combination therewith a mechanism for progressively reducing the retarding effect of such brake shoe during the gradual depletion of the supply of yarn on the reel, thereby to ease progressively the effort and strain imposed upon the action which occurs during each cycle of accelerating or starting the yarn and reel into motion; said mechanism comprising a movable follower which is arranged to bear upon the supply yarn on the reel and thus undergo progressive shifting movement from an initial to a final position during depletion of the yarn, the brake shoe mountings or operating connections comprising a device which is operable or adjustable to relax the braking pressure independently of the cyclical operation of the brake shoe, and a mechanical connection from said follower to said device such that, with the progressive shift of the follower, the device is adjusted gradually to relax the braking pressure and amount of retarding effect upon the yarn reel.

In the accompanying drawings,

Fig. 1 is a left end elevation view of an illustrative warp-knitting machine of the type shown in said prior application and including sufficient

of the mechanism thereof for the disclosure of the novel features of the present invention.

Fig. 2^a is a detail section view taken on the line 2^a—2^a of Fig. 2.

Fig. 2 is a left elevation, similar to Fig. 1, but showing a second form or embodiment of the invention.

Fig. 3 is a similar view showing a third form of the invention.

Fig. 4 is a similar view showing a fourth embodiment.

Referring first to the embodiment of the invention shown in Fig. 1 the bank of yarns *y* is shown to be flowing downwardly from the yarn supply *Y* carried on the reel or warp beam *g* adapted to rotate step by step about a reel shaft *10*, in gear with which, for example as in said prior application, is a shaft *11* carrying a friction disk or drum *12*, which may be the brake disk of the apparatus. In order to apply braking friction to the disk *12* there is at least one, and preferably a pair of opposite friction shoes *13*, at the left side of the figure and *13'* at the right side. The application of the friction shoes for braking the drum and reel is provided by a pair of brake levers, or shoe levers *14* and *14'*, at the left and right, swinging respectively about overhead pivots or axles *15* and *15'*, the hubs *16* and *16'* of the levers engaging directly on the axles.

This arrangement of friction shoes and brake imposing levers corresponds to the illustration in said prior application, the parts herein being however shown in an upright posture for convenience of illustration. In the normal operation of the knitting machine it is necessary during each cycle to relax relatively the braking pressure and friction, and similarly to said prior application this is herein provided as follows. The left and right shoe levers *14* and *14'* respectively are formed with depending lower ends *17* and *17'* which are of different lengths to cooperate with the friction relaxing means illustrated as comprising a shipper device *18*. This shipper is in the form of a rock lever, set upright between the lower swinging ends of the shoe levers and mounted upon an axle *19*, so that when the shipper is rocked in one direction it thrusts apart the free ends of the shoe levers thus to relax the braking pressure thereof upon the disk *12*. Further, as in said prior application, the axle *19* may be a longitudinal rockaxle extending the whole length of the machine and giving support to part of the yarn guiding means as follows. Thus, mounted on the rockaxle *19* are carrier arms *20* supporting at their outer or righthand ends a longitudinal guide rod *21* which constitutes the movable yarn guide rod or pilot adapted to swing floatingly under the pull of the yarn and other operative factors. Thus the yarn *y* is seen to pass from the supply reel at the left side thereof, downwardly and around a fixed guide rod *22*, and thence rightwardly around the pilot rod *21* and downwardly again at a slant toward the knitting point; the drawings showing in full lines the normal or fully elevated position of the pilot *21* and carrying arms *20*, when the yarn is not under raised tension, and in dotted lines a lowered position thereof produced by the tension existing in the yarns during certain parts of each knitting cycle.

These movements of the pilot are spring-controlled by the following additional elements, which provide a predetermined yarn tension, as in the prior application. On the rockaxle *19* is shown a rightwardly extending rockarm *23* which is

pressed upwardly by a long spring 24 surrounding a guiding bar 25 and anchored at its lower end by abutments as in said prior application. By this arrangement the long spring 24 takes the weight of the elements 23, 20 and 21 as well as the stress produced by the downward pull of the tension of the yarns upon the pilot rod 21, thereby to maintain the yarn at the desired tension. Thereby, when the demand for yarn in each cycle causes the resilient lowering of the pilot rod, this swings downwardly the carrier 20 and rockarm 23, compressing the spring 24 until equilibrium is reached; and this action at the same time causes the rocking of the rockaxle 19 and thereby the swinging of the shipper 18, in a clockwise direction, so as to apply a pressure upon the lower ends of the shoe levers tending to swing them apart and thus relax the frictional braking of the disk 12 and reel 9, and so facilitating the necessary slight rotation of the reel to feed in each cycle the length of yarn needed therefor. While the relaxing of the braking action is thus effected, this is in opposition to the brake applying force of a cross spring 27 shown as extending from the left to the right brake lever and thus pulling the opposite brake shoes forcibly upon the brake disk; the mounting of the cross spring upon the right-hand lever 14' being shown as adjustable, by a device or thumb screw 28, to predetermine the maximum braking force. These several parts and their cooperation follow substantially the disclosure in said prior application; it being observed that the motions of the pilot rod are not wholly determined by the length of yarn used for each knitted course or cycle, but largely rather by the yarn manipulating motions of the knitting elements which at one point lap the yarns around the needles, and also by the cooperating motions of other knitting elements; so that during these phases of each cycle it is essential to provide suitable means adapted effectively to maintain the yarns under a practically constant tension.

As already described, as a given supply Y of warp yarns, initially filling the reel 9, becomes used up, the changes in conditions present the problem already described, namely, that progressively the force grows greater that is needed to produce each new short rotary advance movement of the reel and yarn. If the pull of the yarns be the only means for causing such intermittent turns of the reel and the yarn supply then obviously, with the depletion of the yarn supply the strain and tension upon the yarns, thus applied during a short extent of each knitting cycle, must gradually increase as the supply is used up, thus unavoidably introducing irregularities and a decided lack of uniformity in action at the beginning and at the ending of the knitting of any given length of fabric. The change of strain may be injurious to the yarns and at the best involves changes in tension such as to affect objectionably the action of the knitting instruments, and changing the tightness of knitting and other characteristics of the fabric produced. If on the other hand the necessary operation of starting the reel into rotation in each cycle is performed partly by the pull of the yarns and partly by the power drive of the reel, controlled by the yarn pull through the pilot member 21, there still remains a degree of disadvantage, at least to the extent that the yarns tend to undergo progressively increasing tension.

In order to minimize these drawbacks and to offset approximately the progressive ill effects of the depletion of the yarn, the present invention

provides for the gradual reduction of the retarding effect or friction of the braking shoes, calculated and designed to relax the normal friction of the shoes upon the disk, during the gradual depletion of the yarn, thus to materially offset or substantially equalize the tendency to an increase of resistance to the starting of rotation, and thus largely neutralize the objection described.

For these purposes the present invention, in the form shown in Fig. 1, provides the following novel mechanism and operation. Bearing upon the warp yarn supply Y is shown a follower or roller 34 which is carried at the free end of a swinging arm 35 fulcrumed on an axle or pivot 36 in such manner that the follower can swing inwardly from the periphery toward the center of the reel as the yarn is used up, the initial outward position being shown in full lines and the furthest inward position in dotted lines. The swinging movements of the follower arm 35 are utilized to afford the control mentioned, for which purpose the mountings or the operating connections of the brake shoe levers 14 and 14' are provided with a device that is operable or adjustable to relax the braking pressure independently of the cyclical operations of the brake shoes, as will next be described.

Continuing the description of Fig. 1, from the follower arm 35, its pivot 36 is shown as carrying a rockarm 31, extending at an upward outward slant, its free end being slotted for adjustment purposes, and there being a link 38 from said free end to the upper or free end of an adjuster arm 39. Said arm 39 is shown as mounted on an axle or rockshaft 40 located approximately centrally between the fixed axles 15 and 15' of the hubs 16 and 16' of the respective shoe levers. A sufficiently strong spring 41 is applied to these parts, for example pulling rightwardly upon the adjuster arm 39, to hold the follower 34 reliably in contact upon the supply Y of yarn.

The operation of these parts upon the shoe levers, to relax the braking friction of the shoes, is in this instance provided by a short rocker or two-armed lever 42 centrally mounted on the rockshaft 40. The shoe lever hubs 16 and 16' have horizontal or aligned slots 43 and 43' in which are engaged studs 44 and 44'. A link 45 extends from the lower end of the rocker to stud 44 and a similar link 45' from the upper end to stud 44'. The hubs 16 and 16' have a tendency to move apart on their axles 15 and 15' by the springs 32 and otherwise so that the studs 44 and 44' normally rest at the inner ends of the slots 43 and 43'. Therefore, when the adjuster arm 39 is swung rightwardly, with the depletion of yarn supply, the rocker 42 and links 45 and 45' operate so as to allow the hubs to spread or shift apart. This separating action of the hubs brings about the required relaxing of the friction pressure of the brake shoes on the drum, during the gradual depletion of yarn, and independently of the cyclical operation of the brake shoes. Thus, in a sense the shoe levers turn about floating hubs, which initially stand apart to a fixed distance, but which gradually are spread further apart during progress of the knitting. By this described arrangement the connections from the follower 34 to the pressure-relaxing-device 42-45 cause the gradual readjusting of the device so as to reduce the braking pressure and resistance to the rotation of the reel as the yarn thereon becomes used up.

In operation, the resistance to the starting up

of reel rotation in each cycle is presented both by the inertia of the parts to be started and by the frictional resistance of the brake means or shoes 13 and 13' upon the disk or drum 12 which rotates with the reel. The component of resistance which is due to the friction of the brake means is by this invention reduced progressively to offset approximately the increase of resistance due to the lessened radius and leverage of yarn pull on the reel and the need of an increasing angle of rotation to afford the necessary length of yarn in each cycle. The spreading or shifting apart of the fulcrums of the two friction brake levers is herein utilized as a means of progressively decreasing the frictional resistance to each advancing movement of the reel. The actual extent of spreading or separating movement of the fulcrums may be quite small, for example of the order indicated by the throw of the spreading rocker 42. When the opposite lever hubs are thus caused to move apart, the shoe levers are effectively separated by this progressive adjusting means, independent of cyclical operation of the levers from their other or lower ends. When the upper ends of the shoe levers 14 and 14' are thus shifted apart, this may relax the pressure of the shoes 13 and 13' themselves, without any need of the shoes leaving contact with the disk 12. In fact the brake shoes preferably have a slotted or equalizing mounting 31 on the shoe levers as shown, with a pair of springs 32 interposed between each lever and shoe; so that the shoes can not move away from frictional contact with the disk, whereas the spreading apart of the levers relaxes the interposed springs 32 and thus decreases the frictional pressure in the manner and for the purposes already explained.

The second illustrative form of the present invention is shown in Fig. 2, taken with the sectional view Fig. 2a of the details of the shoe lever hub pivoting means. As in the first form the follower 34 is on the arm 35 swinging about the axle 36 which carries also a rockarm 37 connected by a link 38 to the fulcrum adjusting devices. There is shown a lefthand adjuster arm 46 and a righthand adjuster arm 46', these being connected together by a cross link 47, the actuating link 38 being also connected with this system, being pivoted to the adjuster arm 46. The necessary resilient bias to hold the follower on the reel is provided by the pulling spring 41, in this case connected to the adjuster arm 46'.

In this form the shoe arms have floating pivots or hubs provided without the need of loose slot connections as in the first form, the second form providing, for each of the levers, an axle or fulcrum which is in the form of an eccentric and which therefore needs only to be turned to change the effective center or axis of swing of the lever. Describing this device in detail, the adjuster arms 46 and 46' have hubs 48 and 48' within which are eccentric sleeves 49 and 49', these being secured to the hubs 48 and 48' by pins 50. The eccentric sleeve in each case extends through and beyond the adjuster arm hub, and is mounted for rotation upon an interior fixed axle or pivot 15 or 15'. The eccentric sleeve extensions are engaged and surrounded by the hubs 16 and 16' of the shoe levers 14 and 14'. It is therefore clear that as the adjuster arms are swung gradually rightwardly, during the depletion of the yarn, the eccentrics are turned clockwise and thus effect the adjusting shift of the fulcrums of the shoe levers as described. The eccentrics are relatively inverted so as to afford opposite movements to

the lever fulcrums, the eccentric 49 thus having its wider side below the axle 15 while the eccentric 49' has its wider side above the axle 15'; wherefore with the gradual exhausting of the yarn the axis of swing of the lefthand lever is shifted leftwardly while that of the righthand lever 14' is shifted rightwardly. By these means, the inward travel of the follower 34 causes the gradual spreading apart or separating of the fulcrums of the shoe levers to afford the actions already fully described.

The third embodiment of the invention, shown in Fig. 3, while operating on the same broad principles, differs from the other forms in that the progressive relaxing of the braking pressure with the depletion of yarn is brought about not by the use of floating fulcrums for the shoe levers, nor by the shifting of those fulcrums, but by a gradual modification of the resilient or spring force which is the force utilized to pull together the brake levers and shoes. In this illustration the progressive adjustment is effected through the cross spring 27 which supplies the main braking force for the cyclical braking operation, opposed by the separating force provided by the swinging pilot 24 and the shipper lever 18.

Referring to the specific mechanism shown in Fig. 3 the cross spring 27 is shown as having its action modified by a device adjusting one end of the spring, rather than by splitting the spring and interposing a device between its two parts. As before, the follower 34 is on a swinging arm 35 fulcrumed at 36. In this case the arm 35 is supplemented by a shorter arm 52 extending outwardly to the left, thereby to swing upwardly with the consumption of yarn. Extending from the short rockarm 52 is a link 53 the lower end of which is pivoted to the free outer end of a lever 54 which in turn is fulcrumed at 55 upon the lefthand brake shoe lever 14. This lever 54 has, beyond its pivot, a short arm 56, and by a pin 57 or similar mounting the left end of the cross spring 27 is secured thereto.

It will be noted that during ordinary operation, through cycle after cycle, the friction controlling devices cause no interference with the braking operations, since the shipper 18 can swing apart the shoe levers and the spring 27 can draw them together without hindrance from the follower connections. However, with the progressive depletion of the yarn the follower arm 35 swings rightwardly or inwardly thus elevating the outward arm 52 and the link 53, swinging upwardly the lever 54 and inwardly the short arm 56 thereof, which extends in a generally upward direction so that when swung as described it brings about a slight shortening of the spring 27 and thereby a reduction of the spring pull and consequent relaxing of the braking pressure afforded by the spring. It may incidentally be noted that in Fig. 3 the brake-imposing spring 27 is mounted by separate adjusting means at its two ends; at its right end the adjuster 28 is a thumb screw for initial setting of the spring tension, while at the left end of the spring its mounting on the lever arm 56 brings about the automatic lessening of the spring tension throughout the depletion of the yarn on the reel.

The fourth embodiment of the invention, shown in Fig. 4 differs from the other three forms in that the progressive relaxing of the braking pressure during the exhaustion of the yarn from the reel is brought about by a gradual readjustment of the mechanical relation of the shoe levers 14 and 14' to the shipper device by which

those levers are spread apart during each knitting cycle to relax the braking action. As before, the shoe lever 14 is considerably longer than the other, so as to accommodate the shipper lever 18 vertically between their ends. The action of the shipper is that when it is swung by a clockwise turn of the axle 19, its upper end acting through an adjustable contact device 60 presses outwardly on the short shoe lever 14', while a similar contact 61 at the foot of the shipper acts outwardly against the lower end of the shoe lever 14. In each case the mechanical connection is shown as a thrusting one, so that the swinging of the shipper, when the pull of the yarns lowers the pilot 21, causes the thrusting apart of the shoe levers, in each cycle, and therefore, the relaxing of the braking effect, thus aiding the rotating of the yarn reel, whether by the pull of the yarns thereon or by a power drive mechanism.

In this modification the mechanical relation between the shipper and the shoe levers is utilized as follows. Instead of the shipper contact members 60 and 61 pressing against contacts that are mounted fixedly on the shoe levers, said levers are provided with adjustable contacts which may be progressively adjusted during the depletion of the yarn to increase gradually the relaxed condition of the brake levers. In the form shown the contacts on the shoe levers are eccentrics or cams 62 and 63 respectively, pivoted respectively by fulcrum pins 64 and 65 on the shoe levers, and having extension arms 66 and 67 respectively for turning the eccentric contacts to change the adjustments. The two arms 66 and 67 are interconnected by a link 68 compelling the two eccentrics to turn through equivalent angles when operated, the eccentrics being relatively inverted, so that when their arms and the link are shifted there will be opposite and equivalent adjusting actions. When the two eccentric contacts are turned clockwise they operate by reaction against the shipper contacts to thrust apart the shoe levers 14 and 14'. By dotted lines the shifted positions of the adjusting parts are shown.

It is the intention that these adjustments shall be effected by changes in the yarn diameter on the reel, as with the other embodiments. For this purpose the following additional connections are shown. Extending outwardly from the pivot 65 of the eccentric contact 63 is shown a rock-arm 69 which is connected by a long upright link 70 when an outwardly projecting arm 71 mounted on the fulcrum 36 which carries the follower arm previously described, the follower 34 of which bears upon the yarn supply on the reel. By this arrangement, as the yarn is gradually used up, the inswinging of the follower causes the rise of arm 71, link 70 and arm 69, and this operates through the described connections to turn at two eccentric contacts 62 and 63 to change the relations of the shoe levers to the operating shipper, namely, in such manner that as the yarn is consumed, through cycle after cycle, the adjustable contacts 62 and 63 are shifted in a manner progressively to swing or spread apart the lower ends of the shoe levers, thereby relaxing the braking force or friction, in the manner already described, so as to facilitate each restarting of the reel and yarn into rotation for the supplying of yarn to the knitting instruments in each cycle. As before, the force drawing together the shoe levers to apply the brake is supplied by the cross spring 27; and additionally the brake shoes 13 and 13' are caused to maintain continuous fric-

tional contact with the brake drum 12 by means of the local springs 32 providing a resilient thrust between the shoe levers and the shoes floatingly mounted thereon.

5 In review, in all embodiments an automatic progressive adjustment is afforded by this invention, maintaining substantially steady the yarn tension during its depletion and operable from the decreasing diameter of the supply on the reel. Such adjustment is one acting through the frictional braking means which has to be varied during each cycle to permit and then retard the reel rotation; the action hereof being to relax progressively the braking pressure and friction as the 10 supply diameter grows less, so to offset the otherwise increasing resistance to each reel-rotating operation. The yarn tension is thus kept approximately uniform and the pilot through which the yarn governs the braking action in each cycle 15 is caused to have a steady range of swing.

20 A preferred feature of structure is the spring-pressed floating mounting of each frictional braking shoe on its lever, ensuring continuous braking contact of shoe on disk, but yet responding promptly to movements of the lever as the latter is swung to impose or relax braking action in each cycle; this feature being disclosed in said prior application and having utility both with and without the feature of progressive relaxing of friction braking pressure during gradual depletion of yarn as already herein described.

25 There have thus been described several illustrative mechanisms embodying the principles and attaining the purposes of the invention; but since many matters of arrangement, structure, design and operation may be variously modified without departing from such principles, it is not intended to limit the invention except to the extent set forth in the appended claims:

30 40 What is claimed is:

1. In a warp-knitting machine, in combination with a friction brake means adapted to stop the feeding rotation of the yarn reel in each cycle of knitting, a follower bearing movably against the yarn supply on such reel and thereby shiftable gradually from an initial outer position towards a final inner position as the yarn is consumed, and connecting means from the follower to the brake means operable to relax gradually 35 the degree of braking friction in coordination with the reduction of the yarn supply diameter.

45 50 55 2. In a warp-knitting machine wherein is a brake disk connected to rotate with the yarn reel, and a brake shoe (or a pair) movably mounted to apply retarding effect upon the disk; mechanism for progressively reducing the retarding effect of said shoe during the gradual depletion of the supply of yarn on the reel thereby to ease the effort and strain imposed upon the action

friction brake movably mounted to apply retarding effect upon a brake disk connected to rotate with the yarn reel; mechanism for progressively reducing the friction or retarding effect of said brake during the gradual depletion of the supply of yarn on the reel thereby to ease the resistance imposed upon the action which occurs during each cycle of starting the reel and yarn into motion; the same comprising a movable follower arranged to bear upon the supply yarn and thus undergo progressive shifting movement from an initial toward a final position during depletion of the yarn, a device associated with the brake and operable or adjustable to relax the braking pressure independently of the cyclical operation of the machine, and a connection from said follower to said device such that with the progressive shift of the follower the device is adjusted gradually to relax the braking pressure and retarding effect upon the yarn reel approximately in coordination with the depletion of the yarn and to offset the tendency to increased starting resistance due thereto.

4. In a warp-knitting machine shiftable means controlled in position by the diameter of the warp supply on the warp beam, the same being arranged gradually to adjust or diminish the braking force applied to a brake drum connected to the warp beam, and thereby substantially to equalize the force required to rotate the warp beam by the pull of the yarn namely in a progressive manner from a full warp beam with a large circumference and through a decreasing warp circumference, whereby the braking force is gradually diminished to facilitate the accelerated rotation of the warp beam in each cycle by the pulling force of the yarn, thereby to provide automatically a substantially equal supply of yarn through cycle after cycle in the course of knitting the fabric.

5. In a warp-knitting machine a shiftable follower lever controlled in position by the diameter of the yarn on a warp beam to gradually move the pivoting points of a pair of brake brackets, and connections linking said lever to an opposite pair of brake-applying levers or brackets, thereby gradually to reduce the spring force applied to the pair of brake levers, thus automatically to compensate for the increasing resistance to the pulling force of the yarn as required to afford a substantially constant supply of yarn to the knitting elements.

6. A warp-knitting machine wherein are opposed brake levers carrying friction shoes and with a shipper means to spread apart the shoe lever free ends in each cycle against the force of resilient means tending to apply the brake, a follower bearing on the yarn supply on the warp reel thus to undergo progressive inward shift during depletion of yarn, an adjuster device between the shipper axle and the free ends of the shoe levers, said device being adjustable to vary the spread relation of the shoe levers independently of cyclical spreading action of the shipper, and a connection from the follower to said adjuster device arranged to spread gradually the shoe levers and relax the braking friction in coordination with the depletion of the yarn.

7. A warp-knitting machine as in claim 6 and wherein the adjuster device comprises connecting contacts between the shipper and the respective shoe lever free ends, the same being adjustable from the follower to spread the levers relatively to the shipper by reason of the inward shift of the follower.

8. A warp-knitting machine as in claim 6, wherein the adjuster device comprises connecting contacts between the shipper and the respective shoe lever free ends, the same being adjustable from the follower to spread the levers relatively to the shipper by reason of the progressive inward shift of the follower; and wherein each adjuster device comprises a rotary cam or eccentric contact on its lever, opposed to a contact surface on the shipper.

9. In a warp-knitting machine having a friction brake means comprising a shoe carried on a brake lever or carrier and adapted and operated in each cycle to apply friction to retard and stop the warp reel rotation and to relax and release the same; in combination with a follower bearing upon the yarn supply upon the reel to shift progressively inwardly cycle after cycle as the yarn is depleted, a device associated with the brake means adapted to relax the braking pressure and friction thereof independently of the cyclical operation of the brake means, and connecting means from the follower to the relaxing device arranged to cause progressively the relaxing of the braking pressure and friction as the yarn is gradually depleted; thereby to offset the tendency to gradually increasing resistance to restarting the reel rotation in each cycle, whereby the yarn tension is maintained approximately uniform throughout the knitting of the fabric.

10. A warp-knitting machine as in claim 9 and wherein is a resiliently mounted shiftable yarn pilot guide rod having connections for causing the braking and relaxing of the reel in each cycle, and a long supporting spring resisting the shift of the pilot rod under the tension of the yarn.

11. A warp-knitting machine as in claim 9, wherein is a resiliently mounted shiftable yarn pilot guide rod having connections for causing the braking and relaxing of the reel in each cycle, and a long supporting spring resisting the shift of the pilot rod under the tension of the yarn; and wherein the friction shoe has a spring mounting on its carrier lever, holding the shoe in continuous frictional engagement; and the shoe lever is spring pressed to apply the retarding and stopping action.

12. A warp-knitting machine as in claim 9 and wherein the friction shoe has a spring mounting on its carrier lever, holding the shoe in continuous frictional engagement; and the shoe lever is spring pressed to apply the retarding and stopping action.

13. In a warp-knitting machine having a friction brake means comprising a shoe carried on a brake lever and operable in each cycle by moving the lever to impose friction upon a disk thereby to retard and stop the warp reel rotation and thereafter to relax the same for rotation and feed, and means under pilot control from the yarns passing from reel to knitting point arranged to cause in each cycle such imposing and relaxing action of the brake means; and characterized in that the friction shoe has a thrusting spring or resilient mounting on its lever with an action holding the shoe continuously upon the disk, under variable pressure and friction, as the lever is moved toward and from the disk.

14. A warp-knitting machine as in claim 13 and wherein the friction shoe has a slotted floating mounting upon its lever, and its thrusting spring is of such strength and short length as to respond promptly to brake imposing and relaxing movements of the lever.

15. A warp-knitting machine as in claim 13.

wherein the friction shoe has a slotted floating mounting upon its lever, and its thrusting spring is of such strength and short length as to respond promptly to brake imposing and relaxing movements of the lever; and wherein is a cross spring urging the shoe lever in a direction to impose braking action, and adapted to be overcome by the pilot control to relax the braking action; and the pilot control means comprises a long spring which resists the shift of the pilot means under 10 the tension of the yarn.

16. In a warp-knitting machine having for controlling the yarn feeding movements of the reel the following: a friction means controlling the rotation of the reel and comprising a shoe 15 carried on a lever and operable in each cycle by moving the lever to impose shoe friction upon a drum connected with the reel and thereafter to relax such friction, and means under pilot control from the yarns passing from reel to knitting point and arranged to cause in each cycle such friction imposing and relaxing action; and characterized in that the friction shoe is carried on its lever by a thrusting spring or resilient mounting with an action holding the shoe continuously 20 upon the drum, under variable pressure and friction, as the lever is moved toward and from the disk.

17. A warp-knitting machine as in claim 13 and wherein is a cross spring urging the shoe 30 lever in a direction to impose braking action, and adapted to be overcome by the pilot control to relax the braking action; and the pilot control means comprises a long spring which resists the shift of the pilot means under the tension of the 35 yarn.

18. In a warp-knitting machine wherein is a friction brake shoe movably mounted to apply retarding effect upon a brake disk connected to rotate with the yarn reel; mechanism for progressively reducing the friction or retarding effect of said brake during the gradual depletion of the supply of yarn on the reel; the same comprising a movable follower arranged to bear upon the supply yarn and thus undergo progressive shifting movement from an initial toward a final position during depletion of the yarn, a device associated with the brake and operable or adjustable to relax the braking pressure independently of the cyclical operation of the machine, and a connection from said follower to said device such that with the progressive shift of the follower the device is adjusted gradually to relax the braking pressure and retarding effect upon the yarn reel approximately in coordination with the depletion of the yarn; said mechanism being further characterized in the provision of a lever carrying the brake shoe, said shoe lever having its fulcrum adjustably shiftable to vary the braking pressure of the shoe, and the connections from the follower operating to shift such lever fulcrum progressively to relax the braking pressure with the gradual depletion of yarn.

19. A warp-knitting machine as in claim 18 and wherein is an opposed pair of shoes with a carrying lever for each, and a rocker adapted to cause shift outwardly of each shoe lever fulcrum, the connections from the follower operating to turn the rocker and thereby shift the fulcrums. 60

20. A warp-knitting machine as in claim 18 and wherein is an opposed pair of shoes with a carrying lever for each, and a cam adapted to thrust outwardly each shoe lever fulcrum, the connections from the follower operating to turn the cam and thereby shift the fulcrums; and 70

each shoe lever fulcrum comprising a slotted floating hub rotatable and shiftable upon a fixed axle.

21. A warp-knitting machine as in claim 18 and wherein is an opposed pair of shoes with a carrying lever for each, and each shoe lever hub turns upon an eccentric as a fulcrum, and the connections from the follower operate to turn the eccentric and thereby adjust the axis of swing of the lever.

22. In a warp-knitting machine wherein is a friction brake having opposed shoes movably mounted to apply retarding effect upon a brake disk connected to rotate with the yarn reel; mechanism for progressively reducing the friction or retarding effect of said brake during the gradual depletion of the supply of yarn on the reel; the same comprising a movable follower arranged to bear upon the supply yarn and thus undergo progressive shifting movement from an initial toward a final position during depletion of the yarn, a device associated with the brake and operable or adjustable to relax the braking pressure independently of the cyclical operation of the machine, and a connection from said follower to said device such that with the progressive shift of the follower the device is adjusted gradually to relax the braking pressure and retarding effect upon the yarn reel approximately in coordination with the depletion of the yarn; said mechanism being further characterized in the provision of opposed brake shoe levers carrying the friction shoes, with means operating on the free ends of the levers to vary the braking action in each knitting cycle, said shoe levers having their fulcrums adjustable to vary the braking pressure of the shoes, and the connections from the follower operating to adjust apart said lever fulcrums progressively to relax the braking pressure in coordination with the gradual depletion of the yarn.

23. A warp-knitting machine as in claim 22 and wherein is a rocker adapted to cause shift outwardly of each shoe lever fulcrum, the connections from the follower operating to turn the rocker and thereby shift the fulcrum.

24. A warp-knitting machine as in claim 22 and wherein is a cam adapted to thrust outwardly each shoe lever fulcrum, the connections from the follower operating to turn the cam and thereby shift the fulcrums; and each shoe lever fulcrum comprising a slotted floating hub rotatable and shiftable upon a fixed axle.

25. A warp-knitting machine as in claim 22 and wherein each shoe lever hub turns upon an eccentric as a fulcrum, and the connections from the follower operate to turn the eccentric and thereby adjust the axis of swing of the lever.

26. Warp-knitting machine as in claim 22 and wherein each shoe lever hub turns upon an eccentric as a fulcrum, and the connections from the follower operate to turn the eccentric and thereby adjust the axis of swing of the lever; the two eccentric being relatively inverted, each with an upstanding adjuster arm, and said arms being link-connected with each other and the follower.

27. In a warp-knitting machine wherein is a friction brake means having shoes movably mounted to apply retarding effect upon a brake disk connected to rotate with the yarn reel; mechanism for progressively reducing the friction or retarding effect of said brake during the gradual depletion of the supply of yarn on the reel; the same comprising a movable follower arranged to bear upon the supply yarn and thus undergo

progressive shifting movement from an initial toward a final position during depletion of the yarn, a device associated with the brake and operable or adjustable to relax the braking pressure independently of the cyclical operation of the machine, and a connection from said follower to said device such that with the progressive shift of the follower the device is adjusted gradually to relax the braking pressure and retarding effect upon the yarn reel approximately in coordination with the depletion of the yarn; said mechanism being characterized further in the provision of opposed brake shoe levers carrying the friction shoes, with means operating on the free ends of the levers to vary the braking action in each knitting cycle, and a tension pull spring extending across from lever to lever and providing the frictional pressure for the brake shoes, said cross spring having a device for adjusting its tension, and a connection from the follower to said device adapted to operate said device to reduce the tension of the spring progressively with the depletion of the yarn.

28. A warp-knitting machine as in claim 27 and wherein said device comprises a swingable mounting for one end of the spring upon one shoe lever.

29. A warp-knitting machine as in claim 27 and wherein said device comprises a swingable mounting for one end of the spring upon one shoe lever and a manual tension adjusting means on the other lever.

5 30. A warp-knitting machine as in claim 16 and wherein the friction means is a friction brake device for retarding the reel, and comprises a drum and a pair of shoes bearing thereon and levers carrying the shoes, with spring mounting means between levers and shoes causing continuous friction engagement of the shoes upon the drum throughout the feeding period of each cycle.

10 31. In a warp-knitting machine having for controlling the yarn feeding movements of the reel the following: a friction means controlling the rotation of the reel and comprising a shoe carried on a lever and operable in each cycle by moving the lever to impose shoe friction upon a drum connected with the reel, thereby to retard the reel, and thereafter to relax such friction, and means under pilot control from the yarns passing from reel to knitting point and arranged to cause in each cycle such friction imposing and relaxing action; the friction shoe being carried on its lever by a resilient mounting with an action holding the shoe continuously upon the drum, under variable pressure and friction, as the lever is moved toward and from the disk; and characterized further in the provision of a means responsive to the progressive depletion of the yarn on the reel and connected to adjust progressively the friction imposing and relaxing action for reducing gradually the reel retarding effect as the yarn undergoes depletion.
